UNITED STATES PATENT OFFICE.

HENRY H. MARSHALL, OF LINCOLN, NEBRASKA.

CAR-COUPING.

SPECIFICATION forming part of Letters Patent No. 701,594, dated June 3, 1902.

Application filed November 18, 1901. Serial No. 82,711. (No model.)

To all whom it may concern:

Be it known that I, HENRY H. MARSHALL, a citizen of the United States, residing at Lincoln, in the county of Lancaster and State of 5 Nebraska, have invented a new and useful Car-Coupling, of which the following is a specification.

The invention relates to improvements in car-couplings.

10 The object of the present invention is to improve the construction of car-couplings, more especially the means for attaching the same to cars, and to provide a simple, inexpensive, and efficient draft mechanism designed especially for use on passenger-coaches and sleeping-cars and capable of effectively cushioning the longitudinal movement of the draw-head and draw-bar.

15 The invention consists in the construction and novel combination and arrangement of parts hereinafter fully described, illustrated in the accompanying drawings, and pointed out in the claims hereto appended.

20 In the drawings, Figure 1 is a plan view, 25 partly in section, of a portion of a car provided with a car-coupling constructed in accordance with this invention. Fig. 2 is a horizontal sectional view illustrating the manner of connecting the car-coupler to the attachment-frame.

30 Like numerals of reference designate corresponding parts in both figures of the drawings.

1 designates a draw-head provided with a 35 shank or draw-bar 2 and connected by parallel rods 3 with an attachment-frame 4, and the said rods, which are designed to extend the entire length of the car 5 from one draw-head to the other, are provided at their ends 40 with slots 6, receiving keys 7 of the draw-head. The draw-head is provided at its back at opposite sides of the shank or draw-bar 2 with sockets or recesses 8 for the reception of the ends of the draft-rods, which are enlarged 45 and flattened, as clearly shown in Fig. 2. The keys extend vertically through the draw-head, and they may be retained in place by any suitable means, being preferably provided at their upper ends with heads and at their lower 50 ends with suitable fastening devices.

The attachment-frame, which may be of any desired size, is composed of side bars,

and these sides 9, which are connected by a cross-piece 10, are provided with end sockets 11, receiving cushioning or buffer springs 13, 55 disposed on the rods and interposed between the draw-head and the attachment-frame. These coiled springs, which may be of any size and strength, are adapted to cushion the draw-head, the springs at both ends of the 60 car operating simultaneously to cushion both of the draw-heads, which are connected by the continuous draft-rods. The sides of the draft-frame are provided with enlargements and have perforations for the reception 65 of fastening devices 14 for securing them to the frame of a car, and the cross-piece 10 is secured to suitable enlargements 15 at the inner faces of the sides; but it may be formed integral with the sides or constructed in any 70 other suitable manner. The draft-frame is designed especially for sleeping-cars and passenger-coaches, and the ends of the sides having the sockets are arranged flush with the end sill of the car, which is preferably provided with a face-plate 16, plungers 17, and a cushioning-spring 18, constructed as set forth in Patent No. 446,070, granted to me February 10, 1891. The cushioned face-plate and the plungers 17 are designed for use on 75 vestibule-cars, as set forth in said patent.

The shank or draw-bar 2 of the car-coupling is connected with the cross-piece 10 by a tail-bolt 19, and a cushioning-spring 20 is disposed on the tail-bolt and interposed between the cross-piece 10 and the shank or draw-bar. The tail-bolt is secured to the shank or draw-bar by a pin or key 21, and its rear end is perforated for the reception of a similar pin or key 22, located back of the 90 cross-piece 10.

The draft-rods are preferably mounted in longitudinally-aligned guide-openings 38 and 39 of the sides of the draft-frame; but they may be arranged in any other suitable manner, and I desire it to be understood that these and various other changes within the scope of the appended claims may be resorted to without departing from the spirit or sacrificing any of the advantages of this invention.

What is claimed is—

1. The combination of a draft-frame provided with end sockets, a draw-head having

- a shank or draw-bar extending between the sides of the draft-frame and connected with the latter, longitudinal draft-bars connected directly to the draw-head at opposite sides of the shank or draw-bar, and cushioning-springs located at opposite sides of the shank or draw-bar and arranged in the said sockets and interposed between the draft-frame and the draw-head, substantially as described.
- 10 2. The combination of a draft-frame, a draw-head having a shank or bar and provided at opposite sides of the same with recesses located at the back of the draw-head, draft-rods provided with slots or openings arranged in the recesses of the draw-head, keys mounted on the draw-head and passing through the slots or openings of the draft-rods, and cushioning-springs interposed between the back of the draw-head and the draft-frame, substantially as described.
- 15 3. The combination of an attachment-frame provided at opposite sides with longitudinally-aligned openings, draft-rods loosely arranged in the longitudinally-aligned openings, a draw-head having a shank arranged be-

tween the sides of the draft-frame, the back of the draw-head being connected to the draft-rods, and coiled springs disposed on the draft-rods and interposed between the attachment-frame and the draw-head, substantially as 30 described.

4. The combination of an attachment-frame having end sockets and provided with longitudinal openings, draft-rods extending through the openings of the draft-frame and provided at their ends with slots, a draw-head provided at opposite sides with sockets receiving the ends of the draft-rods, keys mounted on the draw-head and passing through the slots of the rods, and springs arranged on the 35 draft-frame and engaging the back of the draw-head, substantially as described.

In testimony that I claim the foregoing as my own I have hereto affixed my signature in 45 the presence of two witnesses.

HENRY H. MARSHALL.
